UNITED STATES PATENT OFFICE.

HARRY O. RASTETTER, OF CANTON, OHIO, ASSIGNOR TO THE UNION METAL MANUFACTURING COMPANY, OF CANTON, OHIO, A CORPORATION OF OHIO.

SHAFT STRUCTURE.

Application filed June 11, 1926. Serial No. 115,230.

This invention relates to sheet metal columns and more particularly to a column of this character adapted especially for use in a shaft construction comprising a pole of 5 rolled steel or the like, for supporting trolley wires, lighting fixtures and similar devices, the steel pole being, for the purpose of ornamentation, surrounded by a shaft comprising a fluted sheet metal column having an 10 ornamental base and capitol.

Where such steel poles are used for supporting trolley wires and similar structures it is necessary that the poles be inspected at 15 stated intervals, and where these poles are surrounded by a sheet metal column, as above described, it is impossible to gain access to the steel pole without dismantling the exterior sheet metal column, which, with the construction of column now in general 20 use involves considerable time and labor.

The object of the present invention is to provide a shaft structure comprising an inner supporting pole of rolled steel or the like surrounded by an ornamental sheet 25 metal column structure which may be quickly and readily dismantled and removed from the structure to permit access to or inspection of the inner pole.

The above and other objects may be accomplished by providing a shaft structure including an inner pole of steel or the like, and an ornamental sheet metal column formed of substantially half-round fluted 35 sections arranged to be quickly attached or detached by means of fastening screws or the like, an ornamental base for said sheet metal column surrounding the steel pole and being preferably formed of a plurality of detached, superposed sections, which may be 40 independently raised from the pedestal portion of the base, when the sheet metal column is removed, to permit inspection of the lower portion of the steel pole, an ornamental capitol for said sheet metal column 45 being suspended from the upper end of the steel pole and telescoping over the sheet metal column, permitting the sheet metal column to be removed without affecting the support of the capitol, and compensating for 50 differences in the heights of the poles, when set up.

An embodiment of the invention is illustrated in the accompanying drawing, in which

Figure 1 is a vertical sectional view 55 through the improved shaft structure, and Fig. 2, a section of the fluted column only on the line 2—2, Fig. 1.

Similar numerals of reference indicate corresponding parts throughout the drawing.

The post 1 may be of tubular cross section, mounted upon a suitable base, such as shown at 2, which is anchored in the usual cement or concrete foundation 3. This post 55 may support a trolley wire, or the like, by means of the usual guy wire or similar means, and may support any desirable lighting fixture, as shown generally at 4, at its upper end.

For the purpose of ornamentation this supporting pole is surrounded by a sheet metal column 5 which is preferably a tapered fluted column as illustrated. This sheet metal column is supported upon a 75 base comprising the cast pedestal portion 6 and one or more superposed, annular base members 7.

The capitol 8 is suspended entirely from the upper end of the supporting pole 1, being preferably supported by means of the tie bars 9 which extend through the annular flange 10, at the upper end of the thimble 11 which is inserted into the top of the pole 1.

The upper end of the fluted sheet metal 85 column 5 is telescoped into the lower open end of the capitol compensating for differences in the height of the pole. Thus it will be seen that the capitol is supported entirely upon the pole 1 and is independent of the 90 ornamental sheet metal, permitting the column to be removed, to inspect the pole 1, without disturbing the capitol.

For the purpose of permitting access to the upper portion of the pole, the tie bars 95 9 may be loosened and the capitol lowered to any desired position upon the pole and held by means of the set screws 12.

In order to provide for quickly and readily removing the sheet metal column 5, to 100 inspect the pole 1, this sheet metal column is formed of two similar half-round sections, each of which has a strip 13 connected to one longitudinal edge, as by spot welding 14, riveting or the like, and arranged to overlap the adjoining edge of the other section of the column, and adapted to be detachably connected thereto as by the screws 15.

In assembling the sheet metal column, joining edge portion of the adjacent section. 30
around the pole, these sheet metal sections are placed in position, upon the base, and quickly connected, by means of the screws 15, and since the strips 13 are upon the inside of the sheet metal column, the appearance of the column from the exterior is not in any way detracted from.

To inspect the pole 1 it is only necessary to 19 remove the screws 15 and detach the fluted sheet metal sections permitting access to the pole. If it is desired to inspect the lower portion of the pole, one or more of the cast iron base sections 7 may be raised upwardly 25 around the pole, permitting access to any portion of the interior supporting pole.

I claim:

1. A shaft structure including a supporting pole, and an ornamental column surrounding said pole and formed of sections detachably connected at their longitudinal edges. 20

2. A shaft structure including a supporting pole and an ornamental column surrounding said pole and formed of sections having overlapping flanges at their longitudinal edges and means for detachably connecting each flange to the overlapping ad- 25

joining edge portion of the adjacent section. 30

3. A shaft structure including a supporting pole, an ornamental column surrounding said pole and a capitol suspended from the upper end of the pole. 35

4. A shaft structure including a supporting pole, an ornamental column surrounding said pole and formed of sections detachably connected at their longitudinal edges and a capitol suspended from the upper end of the pole. 40

5. A shaft structure including a supporting pole, an ornamental column surrounding said pole and formed of sections detachably connected at their longitudinal edges and a base for the ornamental column comprising 45 a plurality of superposed sections surrounding the pole. 45

6. A shaft structure including a supporting pole, an ornamental column surrounding said pole, a capitol suspended from the upper end of the pole and a base for the ornamental column comprising a plurality of superposed sections surrounding the pole. 50

In testimony that I claim the above, I have hereunto subscribed my name.

HARRY O. RASTETTER
